(57) **CLAIM**

The ornamental design for a golf training aid as shown and described.

DESCRIPTION

FIG. 1 is a perspective view of a first embodiment of a golf training aid according to the new and ornamental design; FIG. 2 is a front elevation view of the golf training aid of FIG. 1;

FIG. 3 is a rear elevation view of the golf training aid of FIG. 1;

FIG. 4 is a left side elevation view of the golf training aid of FIG. 1;

FIG. 5 is a right side elevation view of the golf training aid of FIG. 1;

FIG. 6 is a top plan view of the golf training aid of FIG. 1; FIG. 7 is a bottom plan view of the golf training aid of FIG. 1; and

FIG. 8 is a front elevation view of the golf training aid of FIG. 1, showing the design in use;

FIG. 9 is a perspective view of a second embodiment of a golf training aid according to the new and ornamental design;

FIG. 10 is a front elevation view of the golf training aid of FIG. 9;

FIG. 11 is a rear elevation view of the golf training aid of FIG. 9;

FIG. 12 is a left side elevation view of the golf training aid of FIG. 9;

FIG. 13 is a right side elevation view of the golf training aid of FIG. 9;

FIG. 14 is a top plan view of the golf training aid of FIG. 9; FIG. 15 is a bottom plan view of the golf training aid of FIG. 9; and,

FIG. 16 is a front elevation view of the golf training aid of FIG. 9, showing the design in use.

Dash-dot break lines in FIGS. 1-16 depict the bounds of the claimed design, and form no part thereof. The area between the break lines forms no part of the claimed design. The

(Continued)

dash-dash broken lines in FIGS. 8 and 16 show environment and form no part of the claimed design. The remainder of the dash-dash broken lines show portions of the golf training aid that form no part of the claimed design.

1 Claim, 10 Drawing Sheets
